UNITED STATES PATENT OFFICE.

GEORGE BREWER GRIFFIN, OF EDGEWOOD, PENNSYLVANIA, ASSIGNOR TO WESTINGHOUSE ELECTRIC AND MANUFACTURING COMPANY, A CORPORATION OF PENNSYLVANIA.

FUSIBLE CUT-OUT.

1,070,452.

Specification of Letters Patent. Patented Aug. 19, 1913.

Application filed October 31, 1910. Serial No. 589,914.

To all whom it may concern:

Be it known that I, GEORGE B. GRIFFIN, a citizen of the United States, and a resident of Edgewood, in the county of Allegheny and State of Pennsylvania, have invented a new and useful Improvement in Fusible Cut-Outs, of which the following is a specification.

My invention relates to fusible cut-outs for transformer or other electric circuits and it has for its object to provide a cut-out of the above indicated class which shall be simple and inexpensive in construction and effective and reliable in operation, and which shall be particularly adapted to relieve the excessive pressure created at the instant the fusible material is blown and to rapidly discharge the hot metallic vapor thus formed under such conditions as to prevent injury to the hands of anyone who inserts the detachable member of the device at any time during the existence of an overload or a short circuit on the line.

In the past, it has been common practice to employ cut-outs of the general type herein set forth in which openings to the atmosphere have been provided for the purpose of ventilation. However, all such devices have embodied either side or bottom openings which did not always serve to discharge the vapors produced by fuse explosions in such manner and with such effectiveness as to prevent breakage of the fuse-holding receptacle or insure freedom from injury to anyone who might manipulate the device when connected in circuit. Moreover, the life and effectiveness of such cut-outs have been materially reduced on account of the maintenance of severe arcs by metallic vapor which has not been properly discharged.

Investigation has shown that, when fuses of any type which are not tightly embedded in a gas-suppressing material are blown, metallic vapors of extremely high temperature are formed. Such vapors tend to rise with a very considerable speed until the gases which are given off from the minute particles are dissipated and the particles become sufficiently chilled to check the rapid upward movement.

In order to utilize the inherent properties of these hot metallic vapors toward the desired end of quickly discharging the same and extinguishing the arcs which they tend

to maintain, I locate the openings to the atmosphere at the top of the cut-out. Moreover, I provide discharge openings of such form, as well as location, that the cut-outs may be employed for out-of-door service without sacrificing any of the desirable features or advantages.

In the accompanying drawing Figure 1 is a view, partially in elevation and partially in vertical section, of a fusible cut-out constructed in accordance with my invention, and Fig. 2 is a bottom plan view of the cut-out shown in Fig. 1.

Referring to the accompanying drawings, a fusible cut-out 1 comprises a fuse-holding body or plug 2 and a supporting block or receptacle 3, both of which are constructed of porcelain or any other suitable insulating material.

The fuse-holding body 2 comprises a frusto-conical projecting body portion 4 and a knob or handle 5, a shoulder 6 being provided at the lower portion of the projecting body 4 upon which a plurality of movable contact terminals 7 are mounted in a suitable manner at diametrically opposite points. The contact terminals 7 are of the usual knife-blade type and embody a main blade member 8 having an enlarged portion 9 for a purpose which will be hereinafter described.

In proximity to the movable contact terminals 7 are located longitudinally disposed grooves 10 which extend upwardly in the sides of the projecting body portion 4 and communicate with each other at the top. It will be observed that the grooves 10 are gradually deeper and wider at the top, while the lower ends 10a are merely large enough to accommodate a fuse wire 11 which is disposed in said grooves and the ends of which are secured to the stationary contact terminals 7 in a suitable manner. Thus, the fuse wire is well protected and an exceptionally long path is provided. Furthermore, adequate provisions are made for a ready upward discharge of vapors, while a downward expulsion thereof is prevented by reason of the decreased size of the grooves 10a.

The supporting block or receptacle 3 embodies a centrally located frusto-conical recess 12 which extends upwardly and is provided at its lower portion with an enlarged opening 13 and a shoulder 14. Suitable stationary contact terminals 15 are fastened to

the shoulder 14 at diametrically opposite points and coöperate with the movable contact terminals 7 in a well known manner.

In order that the weight of the fuse-holding body 2 may be sustained by the coöperating contact terminals, each jaw 16 of the stationary contact terminals 15 is provided with an outwardly bent portion 17 which is adapted to engage the enlarged portion 9 of the movable contact terminals 7, as will be readily understood. Although these particular types of terminals are specially adapted to perform the functions desired, it is evident that any other suitable devices for accomplishing the same purpose may be employed.

The lower portion of the receptacle 3 constitutes an annular wall 18, in which upwardly projecting holes 19 are provided to accommodate line conductors 20 which are secured to stationary contact terminals 15. Bosses or lugs 21 are also provided on opposite sides of the receptacle 3 for the purpose of mounting said receptacle in its operative position.

The upper portion of the receptacle 3 forms a cap 23 which is overhung on all sides to a considerable extent. Furthermore, a passage 24 is provided which constitutes an upper extension of the recess 12, while a plurality of passages 25 extend from the upper end of the passage 24 to the atmosphere. The passages 25 extend outwardly and downwardly and are open to the atmosphere on the under side 26 of the cap 23. It will be observed, therefore, that, while the hot metallic vapors which are formed at the instant the fuse is blown, are allowed to rise freely and are thus rapidly discharged, suitable weather protection is provided for the discharge openings so that a structure is obtained which may be successfully used in out-of-door service.

Those skilled in the art will readily understand that various modifications may be effected from what is hereinbefore shown and described, without departing from the spirit and scope of my invention, and all such modifications are intended to be covered in the appended claims.

I claim as my invention:

1. A cut-out comprising a supporting block having a frusto-conical central chamber and a passage extending from the top of said chamber to the atmosphere, a movable fuse-holding frusto-conical body having diametrically opposite grooves to receive a fuse wire and adapted to fit into said central chamber, and coöperating stationary and movable contact members secured, respectively, to said supporting block and to said fuse-holding body.

2. In an electrical cut-out, the combination with a supporting block of insulating material having an axially located recess

extending upwardly from its lower surface, a passage extending upwardly and outwardly from said recess to the atmosphere, and stationary contact terminals secured to its base, of a fuse-holding body of insulating material adapted to fit closely in said recess and having contact terminals adapted to coöperate with said stationary contact terminals and longitudinally disposed grooves to receive a fuse wire. 70

3. In an electrical cut-out, a supporting block of insulating material, having a deep recess extending upwardly from the bottom of said block, a projecting body having oppositely disposed grooves to receive a fuse wire and adapted to fit tightly into said recess, stationary and movable coöperating contact members associated respectively with said block and said body, and a passage extending from the top of said recess to the atmosphere, having a downwardly directed outer end. 75

4. In an electrical cut-out, the combination with a supporting block of insulating material, having a deep recess extending upwardly from the bottom of said block, a projecting body having oppositely disposed grooves to receive a fuse wire and adapted to fit in said recess, and stationary and movable coöperating contact members associated, respectively, with said block and said body, said supporting block having a passage that extends upwardly from the upper wall of said recess and has outward and downward extensions to conduct away the vapors formed when the fuse wire is blown and discharge them in a downward direction to the atmosphere. 95

5. The combination with a supporting block having a centrally located frusto-conical chamber extending upwardly from the bottom of said block, a passage extending upwardly a material distance from the top of said recess and thence outwardly and downwardly to the atmosphere and stationary contact terminals at its base, of a frusto-conical plug of the same general size and shape as said chamber and adapted to fit therein and having longitudinal grooves in its sides to receive a fuse wire, and contact terminals adapted to coöperate with said stationary contact terminals to lock said plug and block together. 105

6. The combination with a receptacle of insulating material comprising a body portion having a centrally located upwardly extending recess, a vertical passage constituting an extension of said recess, an overhanging cap portion provided with lateral extensions of said vertical passage which are open to the atmosphere at its underside and stationary contact terminals, of a plug member of insulating material adapted to be inserted longitudinally into said recess, said plug having correspondingly located grooves to 110

receive the fuse wire and contact terminals for said fuse wire which are adapted to co-operate with said stationary contact terminals.

- 5 7. A fusible cut-out comprising an insulating receptacle of inverted cup shape, stationary contact terminals attached to the bottom edge of said receptacle, a fuse-holding plug of insulating material detachably
10 mounted in said receptacle and provided with contact terminals to coöperate with the stationary contact terminals, and a longitudi-

dinal passage having one or more laterally extending branches opening to the atmosphere at the end remote from the contact 15 terminals for discharging the vapor of a blown fuse.

In testimony whereof, I have hereunto subscribed my name this 26th day of October 1910.

GEO. BREWER GRIFFIN.
